UNITED STATES PATENT OFFICE.

WITCHER S. SETTLE, OF MISSOULA, MONTANA, ASSIGNOR TO DAVID STONE,
OF NEW YORK, N. Y.

DESIGN FOR A BADGE.

SPECIFICATION forming part of Design No. 24,749, dated October 15, 1895.

Application filed July 24, 1895. Serial No. 567,063. Term of patent 3½ years.

To all whom it may concern:

Be it known that I, WITCHER S. SETTLE, a citizen of the United States, and a resident of Missoula, in the county of Missoula and State of Montana, have invented and produced a new and original Design for a Pin or other Article, of which the following is a specification, reference being had to the accompanying drawing, in which is shown a plan view 10 of an article containing the design.

The leading feature of the design consists of the crescent composed of the representation of the series of overlapping disks tapering in size from the center to the ends of the

crescent and an independent disk within the 15 field of the crescent, substantially as shown in the accompanying drawing.

The article bearing the design may be provided with any suitable attaching means—
for instance, with a pin. 20

What I claim is—

The design for a pin or other article substantially as shown and described.

WITCHER S. SETTLE.
